(57) **CLAIM**

The ornamental design for a vehicle body, as shown and described.

DESCRIPTION

FIG. 1 is a front, side and top perspective view of a vehicle body showing the new design; and

FIG. 2 is a rear, opposite side and top perspective view thereof; and,

FIG. 3 is a side view thereof, the opposite side being a mirror image of that shown.

In the drawing views, the grille, tires, roof rack, emblems and wheels shown in the broken lines are for illustrative purposes only and form no part of the claimed design.
